ROTARY PRINTING MACHINE

Frank C. Marquardt, New York, N. Y., assignor
to American Bank Note Company, New York,
N. Y., a corporation of New York

Application May 28, 1938, Serial No. 210,613

26 Claims. (Cl. 101--155)

The invention relates to rotary printing machines, and more particularly to a machine of this type for making impressions from engraved, intaglio or undersurface steel printing plates.

5 In printing from engraved, intaglio or undersurface printing plates, ink is applied to the entire surface of the plate, and this surface is then wiped and polished, the wiping of the plate serving to fill and pack the lines of the plate with ink and remove surplus ink from the plate. The 10 polishing of the plate is for the purpose of removing any ink which may be left upon the top or non-printing surface of the plate by the wiping cloths.

15 While, when printing from flat plates, a wiping mechanism is used, the polishing of the plate is usually by hand. With a rotary plate, however, mechanical wiping and polishing mechanisms must both be used, since the plate is inaccessible 20 for hand polishing and the plate cylinder continuously rotates.

25 The bending of steel plates for use upon the cylinder of a rotary printing machine is not only a difficult procedure, but one involving considerable expense and loss because of the accidental destruction of plates.

30 Rotary printing machines of the type to which the invention relates, were in use for many years prior to my present invention, and in such machines, as well as in machines printing from flat plates, there has been an accepted rule for many years that an effective wiping and polishing of the plate cannot be secured with a movement of the plate in excess of a rate of about seventy feet per 35 minute.

35 In machines for printing from flat plates it has been the custom for many years to use four plates upon the machine, in order to secure a suitable output, such machines with four plates, being 40 capable of making about twelve impressions per minute.

45 In rotary machines, however, the practice has been to operate these machines at about eight revolutions per minute, and to use two or sometimes three plates upon each machine, in order to have an output of sixteen or twenty-four impressions per minute, eight impressions to each plate upon the plate cylinder.

50 In printing from engraved, intaglio or undersurface plates, the wastage due to an improper packing of the lines of the plate by the wiping and polishing cloths is always high, and the speed of operation of machines using such plates has been limited to the speed stated above because of limitations in the effective action of the wiping and 55 polishing cloths.

55 The pressures used in making impressions from the plates are very great, and the rapid breaking down of the make-ready upon the impression cylinder or D-roll has resulted in a substantial loss

in the average daily output of such machines. The avoidance of rapid destruction of the make-ready of the impression cylinder or D-roll has also been a factor in limiting the speed of operation of such presses. 5

With the use of high pressures, vibration about the machine is great, even at the speed of operation above indicated, and the intermittent engagement and disengagement of the impression cylinder or D-roll with the plate has been a large 10 contributing factor in the development of such vibration.

15 It has long been endeavored to provide a rotary printing machine of the type to which the invention relates, having an output, with the use of a single plate, substantially equaling the output obtained with a plurality of plates.

20 Such a machine is disclosed in the patent to A. H. Smith, No. 1,511,307, by which machine it was attempted, by the use of a cylinder of small diameter, to increase the number of revolutions per minute of the machine without increasing the rate of movement of the plate beyond that which in multiple plate machines has been found to give 25 satisfactory operating conditions. 25

25 The difficulties encountered with the machine of the Smith patent were the inability to bend or curve the plates upon an arc of the short radius required by a plate cylinder of small diameter, and of securing a proper wiping and polishing of 30 the plate with higher cylinder speeds.

35 With the above conditions in mind, I have produced a rotary printing machine using thereon intaglio, steel or undersurface printing plates which, with a single plate, has an output of two 40 or more times the output of the machines of this type heretofore used, when two plates were used upon such machines. This result has been secured by so constructing the wiping and polishing mechanisms as to minimize vibration in these 45 parts, and irregular movement thereof due to inertia when reversing the direction of movement of the bars, and by reducing the reciprocatory speeds of these bars while in contact with the plates, although, as measured by the number of revolutions per minute of the plate cylinder, the number of reciprocations of said bars per minute is materially increased as compared with a machine 50 operating at lower speeds.

55 In addition to the use of wiping and polishing bars of light, rigid material having high compressive strength, I provide other attachments and adjustments ensuring a smooth movement of the bars, and adjustment devices permitting a proper timing in the operative moment of the 55 different bars in order to secure an effective wiping action at higher speeds of the plate.

60 In order to reduce vibration resulting from wear upon the bearing ends of the wiper bars and the bearings co-operating therewith, I provide a 60

special form of adjustable bearing for each end of the wiper bar, capable of minute and accurate adjustment, so as to develop and maintain a desired pressure relation between the platens carried by the wiping and polishing cloths and the entire area of the plate upon the plate cylinder.

In conjunction with the details of the wiper and polisher bar mechanisms above referred to, I provide accurate micro-metrical adjustment means for maintaining uniform pressure of the impression cylinder or D-roll throughout the entire contacting area of this D-roll with a plate upon the plate cylinder while making an impression. This adjustment is one which is required because of the varying conditions in different plates which may be used upon the plate cylinder.

I have found, in the actual operation of a machine embodying the invention, that the weight of the wiper and polisher bars, the provision of means for ensuring a smooth reversal in the direction of movement of such bars, the speed of reciprocatory movement of the bars, and the timing in the operative moment of one bar in relation to the other, are important factors in permitting the development of a high number of revolutions per minute of the plate cylinder with a corresponding high rate of output of the machine.

While other features of the machine contribute toward its high operating speed, the controlling factor in printing from engraved, intaglio or undersurface printing plates is the proper packing of the lines of a plate with ink, and a proper removal of all ink from the top or non-printing surface of the plate, so as to avoid smudges upon the imprint.

The invention consists in the novel features of construction and combination of parts herein-after set forth and described, and more particularly pointed out in the claims hereto appended.

Referring to the drawings,

Fig. 1 is a side elevation of the printing couple and the wiping and polishing mechanisms of a machine embodying the invention, portions of the frame of the machine being broken away;

Fig. 2 is a perspective view, partly broken away, showing the details of construction of one of the wiper or polisher bars;

Fig. 3 is a chart illustrating the reciprocations of the wiper and polisher cloths in machines used prior to the invention;

Fig. 4 is a similar chart illustrating the reciprocations of the wiper and polisher cloths in a machine embodying the invention;

Fig. 5 is a condensed plan view of the D-roll adjusting mechanism;

Fig. 6 is a detail view upon a larger scale of the mechanism operating at either end of the impression cylinder or D-roll;

Fig. 7 is a detail end view of one of the wiper or polisher bars showing the adjusting mechanism for regulating the pressure relation between the platen of said bar and the plate upon the plate cylinder;

Fig. 8 is a detail view, partly broken away, of the adjusting mechanism for each of the eccentrics upon the wiper bar eccentric shaft and the polisher bar eccentric shaft, for securing a proper timing of the movements of said bars in relation to each other and the counterweight for the eccentric shaft; and

Fig. 9 is a detail view of a fragmentary portion of the impression cylinder or D-roll, showing the construction thereof adjacent the point of en-

gagement of the makeready with the forward edge of the plate upon the plate cylinder.

Like numerals refer to like parts throughout the several views.

In the accompanying drawings, all parts of the machine, excepting the members of the printing couple, the wiping and polishing mechanisms and the adjustment for the impression cylinder or D-roll, are omitted, since such details form no part of the present invention.

As shown in the accompanying drawings, the plate cylinder 13, having mounted thereon a single plate 11, is mounted in fixed bearings in the machine. The impression cylinder or D-roll 12 is mounted in vertically adjustable bearings, adjusting means being provided by which simultaneous parallel movement may be imparted to both ends, or a differential adjustment may be made of the opposite ends, of the impression cylinder or D-roll, toward or from the plate cylinder, to regulate the pressure developed while making an impression upon a sheet of paper.

The impression cylinder or D-roll adjusting mechanism, shown in Figs. 5 and 6, will later herein be described in detail.

The frame of the machine is indicated at 13. The inking mechanism is positioned at the left of Fig. 1. The plate cylinder in said figure has a counter-clockwise movement.

The mechanisms used for applying power to the plate cylinder, and therefrom to the impression cylinder or D-roll, are old and well known in this art and therefore are not shown in the accompanying drawings, it being merely necessary to state that the plate cylinder and the impression cylinder or D-roll have co-operating gears to cause the rotation of both cylinders at a uniform peripheral speed.

The relative diameters of the plate cylinder and the impression cylinder or D-roll are such as to have the latter make two revolutions to one revolution of the plate cylinder. This is the arrangement usually employed with a printing machine in which two plates are used upon the plate cylinder. The ratio of the plate cylinder and the impression cylinder or D-roll may be varied, however, it being a common practice in printing machines in which three plates are used, to use an impression cylinder or D-roll whose diameter is in the ratio of 1 to 3 as to the plate cylinder.

By reference to Fig. 1 of the drawings, it will be noted that the wiping and polishing of the plate occurs while the plate is passing about the lower circumference of the plate cylinder, so that when a single plate is used, while it is being wiped, there is no pressure exerted upon the plate cylinder by the impression cylinder or D-roll. The make-ready of the impression cylinder or D-roll is spaced from the surface of the plate cylinder a distance approximating the thickness of the printing plate, but sufficiently less than this distance to ensure the development of the necessary pressures. Accuracy of adjustment of this relation of the members of the printing couple avoids some of the vibration which develops with the operation of the machine.

In the machine shown in the drawings, two wiping bars and one polishing bar are used, this being a practice long followed in the art. The construction of each wiper or polisher bar is the same as that of every other bar. The two wiper bars are actuated from eccentrics upon the same shaft and the polisher bar by an eccentric on a separate shaft by means of eccentric strap and

link connections known in the art and therefore not shown in the drawings.

The wiper and polisher bars extend from side frame to side frame of the machine, below the plate cylinder. The opposite ends of each bar are provided with polygonal bearing portions. Each bar is provided with an enlarged platen head covered by several plies of felt or other suitable yieldable material permitting the wiping or polishing cloth to adapt itself to slight surface irregularities or flurries in the plate resulting from the bending or tempering of the plate. It is a common practice to use a single web of wiping material successively passing over the platens of the two wiping bars, and a single web of polishing material passing over the platen of the polishing bar.

The general arrangement heretofore described is old and well known, the structure shown in the accompanying drawings varying from corresponding structures used prior to the invention in the following respects:—

The wiping and polishing bars are each made of a metal having a specific gravity lower than steel, but high compressive strength, this being a characteristic of certain aluminum alloys. The design of the bar is also such as to provide the desired stiffness intermediate the ends of the bars with a small mass of metal.

As shown in Fig. 2 of the drawings, the flattened extended head of the bar 14 is provided with a central, longitudinally extending web 15 merging into the bearing ends 16 and 17 which are polygonal in shape, to prevent any turning of the bar. The felt covering for the bar is indicated at 13, several plies of that material ordinarily being used. By using light weight metal in the bar, and limiting the mass of such material as much as is consistent with the retention of the desired strength in the bar, the moving inertia developed by the bar is reduced to a minimum and that vibration or tremble of the bar resulting in chattering, when reversing the direction of its movement is substantially eliminated. This feature is of major importance because slight chattering of the bar during its vibratory movement at the opposite ends of each stroke tends toward an imperfect wiping action. The inability to avoid such chattering, was one of the contributing causes limiting the speed of the machine, and the elimination of such chattering, therefore permits operation of the machine at higher speeds. In fact, as will more fully appear hereinafter, the machine of the invention may be operated at approximately four times the speed of the old type machines, the avoidance of such chattering, or of any hesitancy in the reversal of the movement of the wiper and polisher bars, being a material factor in the development of such higher speeds.

The wiper driving shaft is shown at 19, and the eccentric shaft driving both wiper platens is shown at 20. The shaft 20 is connected with the shaft 19 by a speed reducing gearing 21, the speed ratio of said gears, in the form of the invention shown, being substantially 11 to 8, with the shaft 20 having the lower speed.

Carried by the eccentric shaft 20 are two eccentrics 22 and 23, one adjacent each wiper bar. Power is transmitted from the eccentric 22 to its wiper bar by a strap and link connection 24, and power is transmitted from the eccentric 23 to its wiper bar by a strap and link connection 25. The strap and link connection used is of old and well known construction.

Each eccentric 22—23 is mounted for circum-

ferential adjustment about the shaft 20 by a mechanism shown in detail in Fig. 8, to be later described herein.

While this adjustability of the eccentrics is to permit a desired setting of the eccentric when assembling the wiping mechanism, it is primarily for the purpose of permitting a differential setting of the two eccentrics 22 and 23 to time the movement of the wiper bars actuated from said eccentrics to secure a controlled crossing of the lines of wipe of webs fed across these bars in relation to each other, as shown in Fig. 4 of the drawings. This is done by advancing the stroke of one bar in relation to the other.

Carried by the shaft 20 is a counterweight 26, 15 the greater mass of metal of which is preferably so positioned as to be most effective at each end of the stroke of the wiper bar. Because of the adjustability of one eccentric in relation to the other, the setting of the counterweight in relation to the eccentrics can be only approximate. This counterweight not only secures a balanced condition about the eccentric shaft, but also, at least partially, counteracts the weight of the wiper bars.

The first wiper bar is indicated by the reference numeral 14a in Fig. 1 of the drawings, and the second wiper bar by the reference numeral 14b.

The polishing mechanism embodies a single 30 polishing bar 14c, driven from a polishing bar eccentric shaft 27 by means of an eccentric 28 and a connection, consisting of the usual strap and link construction 29, between this eccentric and the polishing bar.

The shaft 27 is driven from a polisher driving shaft 30. This shaft 30 preferably has a speed in relation to the shaft 19, in a ratio of 4 to 3. The shaft 27 is connected with the driving shaft 30 by the connecting gearing 31, the ratio of 40 the gears of which is substantially 4 to 3. The eccentric 28 is adjustably mounted upon the shaft 27 by a mechanism corresponding with that used in mounting the eccentrics 22 and 23 upon the shaft 20. The adjustability of this eccentric is 45 for the purpose of timing the polishing action in relation to the crossing of the lines of wipe of the wiper bars.

Carried by the shaft 27 is a counterweight 32 having the same construction and setting as the 50 counterweight 26 upon the wiper shaft 20, and having the same action in avoiding vibrations in the polishing mechanism at the opposite ends of each stroke of the polishing bar.

While, with an eccentric and strap drive, there 55 will be a varying speed of movement of the bars from one dead center to the opposite dead center, the use of counterweights, in the manner described, upon the eccentric shafts, will act much in the same manner as a flywheel in securing 60 a smooth passing of the dead centers.

In the embodiment of the invention shown in the drawings, the shaft 19 has approximately 22.5 revolutions, and the shaft 30 approximately 30 revolutions, to each rotation of the plate cylinder. 65 With the speed ratio described between the shafts 19 and 30 and the plate cylinder, and between said shafts respectively and the wiper and polisher shafts 20 and 27, each wiper bar will have one full reciprocation with slightly more than five and 70 one-half inches of travel of a plate upon the plate cylinder, and the polisher bar will have one full reciprocation with slightly over four inches of travel of the plate.

While, in actual practice, these conditions have 75

given highly satisfactory results, so far as clean wiping and polishing of the plate is concerned, it is obvious that the figures given are not critical. It may be added that when making thirty impressions per minute, the peripheral speed of the plate cylinder is approximately 260 feet per minute, or almost four times the speed of ordinary rotary presses of the type to which the invention relates. The various speed ratios given are suitable for even a higher speed than thirty revolutions per minute of the plate cylinder, however.

With speeds greatly in excess of those given, vibrations interfering with the proper wiping and polishing of a plate develop.

15 The stated number of impressions per minute is with the use of a single plate 11.

The steel plate, with conditions as shown in the accompanying drawings, will extend throughout slightly less than one-quarter of the periphery 20 of the plate cylinder, although such plates vary not only as to length but as to width.

The amount of pressure exerted between the wiping web and the plate upon the plate cylinder is slightly greater than the pressure required 25 between the polishing web and the plate. The latter is required only to remove any ink from the non-printing surface of the plate which has been left by the wiping web, while the wiping web is required to fill and pack the lines of the 30 plate with ink in addition to removing, by absorption, excess ink from the non-printing or top surface of the plate.

While both the wiping and the polishing webs are advanced for a short length following each 35 wiping and polishing operation, the wiping webs become heavily saturated with ink, and this is relied upon in large measure to secure a more effective filling and packing of the lines of the plate. Such saturation of the wiping web, however, may result in slight ink streaks upon the 40 top or non-printing surface of the plate, but these will be removed by the polishing web.

Another cause of excessive vibration in a machine of the type to which the invention relates, 45 has been the result of violent impact between the makeready of the impression cylinder or D-roll at the rear of the recess in said cylinder, with the forward edge of the plate. To avoid vibrations from this source, this edge of the recess in, or "nose" of, the impression cylinder or D-roll is formed upon a curve of long radius merging into the periphery of the impression cylinder or 50 D-roll in a manner to ensure a smooth, initial rolling contact between the makeready upon said cylinder and the forward edge of the plate.

This construction is shown at 33 in Fig. 9 of the drawings, the makeready sheets being shown at 55 34 and the outer blanket at 35. The manner of mounting the makeready upon the impression cylinder or D-roll is that commonly employed prior to the invention.

By making the portion or nose 33 upon a curve of long radius as described, the jar of initial impact between the impression cylinder or D-roll and the plate 11 is practically eliminated, and damage to the makeready requiring stoppage 60 of the machine to effect repairs, is avoided.

In a machine embodying the invention using 65 extremely heavy pressures and operating at the high speeds of which the machine of the invention is capable, violent impact of the impression cylinder or D-roll and the plate upon the plate cylinder, due to a high speed of rotation of said cylinders, thus setting up continuing vibrations

which interfere with the proper wiping and polishing of the plate, is avoided.

In Fig. 7, of the drawings, I have shown a view at one end of one of the bars 14a, 14b or 14c of the pressure adjusting and regulating 5 mechanism for each wiper or polisher bar, this mechanism being duplicated upon the opposite ends of each wiper or polisher bar.

In machines prior to the invention, the bearing ends of the wiper and polisher bars passed 10 through side bearing openings in the side frame of the machine and were mounted between an upper and a lower bearing member. The lower member was spring supported, and the upper member was acted upon by an adjusting screw 15 by which the tension of the spring and the pressure relation between the platen and the plate, arising from the action of this spring, were determined. With this construction, the spring support for the lower bearing members, with impact of the forward edge of a plate with the head of a wiper or polisher bar, yielded, and tended to set up continuing vertical vibrations in the wiper and polisher bars which, with the operation of the machine at higher speeds, was 20 found to interfere with a proper wiping and polishing of the plate and packing of the lines 25 therein.

To overcome this difficulty, I provide rigidly supported bearings for the ends of the wiper and polisher bars, and control the pressure relation 30 between the platen of said bar and a plate upon the plate cylinder, by adjustment of the bearings for the ends of the wiper bar toward and from the plate cylinder, so that the pressure relation 35 between the platen and the plate is determined by the setting of the bars and the flexibility or compressibility of the material of the platens carried thereby.

Referring to Fig. 7 of the drawings, the side 40 frames of the machine are provided with bearing openings 36 for the passage of the ends of the wiper and polisher bars. Slidably mounted upon the frame of the machine at each bearing opening, by means of four posts 37, is a top bearing plate 38 and a bottom bearing plate 39 of anti-friction metal. The top and bottom bearing plates 38 and 39 are attached to the posts 37 and have a close sliding fit with the bearing end 16 or 11 of the wiper or polisher bar. 50

Each movable bearing member composed of the posts 37 and the top and bottom bearing plates 38 and 39 is slidably mounted in relation to the side frame of the machine to permit them to be vertically adjusted to secure the desired 55 pressure relation between the platen of a wiper or a polisher bar and a plate 11 by an adjustable supporting mechanism permitting no vertical movement of the bearings after they have once been adjusted.

This supporting mechanism consists of an extension 40 carried by the lower bearing member, and having a T-slot 41 toward the bottom thereof. Mounted in this T-slot is the enlarged head 42 of a micrometer screw 43 having screw threads 65 44 co-operating with screw threads upon a vertically adjusted rack 45. This rack constitutes a part of an old and well known form of throwoff mechanism for moving the wiping and polishing bars out of their plane of engagement with the 70 plate 11 to permit the threading of the wiping or polishing web through the machine, and forms no part of the present invention. Hence, it is not shown in detail.

Carried by the housing 46 for the rack 45 is 75

an index finger 47 co-operating with a graduated sleeve 48 carried by the micrometer screw 44. The screw 44 is provided with an actuating handle 49 by means of which the micrometer screw and the sleeve 48 carried thereby, may be turned to secure a desired minute adjustment of the wiper or polisher bar, as indicated by the 5 graduations upon the sleeve 48. The sleeve 48 is provided with a series of notches engageable 10 with a spring lock member 51 for holding the micrometer screw against displacement as a result of vibration in and about the machine.

Acting upon the top bearing plate 38 is a 15 spring 52 inclosing a spring stud 53 upon the bearing plate. The sole function of this spring is to take up any possible minute looseness between the block 40 and the head 42 of the adjusting screw, and it has no use in preventing the development of vertical vibrations in the 20 wiper or polisher bars as a result of the impact of the plate therewith. If desired, this spring may be dispensed with.

Another source of the development of vibrations in and about the machine which, prior to 25 the invention, necessitated the operation of the machine at low speed, was an inaccurate setting of the D-roll in relation to the plate cylinder. Curved steel plates and the position of these 30 plates upon the plate cylinder during the make-ready of the machine, may result in the surface of the plate, at one side, being spaced from the impression cylinder, a greater distance than at the other side. When the bearings for the arbors at opposite ends of the impression cylinder or 35 D-roll are independently adjustable, it is difficult to properly regulate the pressure toward the opposite ends of this cylinder, particularly when it is understood that very heavy pressure must be exerted by the impression cylinder or D-roll 40 upon the plate on the plate cylinder.

In the embodiment of the invention shown in the drawings, the arbors of the impression cylinder or D-roll are mounted in bearings 54 formed in a bearing block 55 slidably mounted in the side frames of the machine. Each bearing block is supported by a spring 56 which is a 45 part of the impression cylinder or D-roll throw-off mechanism. It forms no part of the present invention and is not shown or described in detail, beyond the co-operating cams 57 operative upon 50 each block, the relative movement of these cams in one direction moving the bearing block against the tension of the spring 56, and relative movement in the other direction permitting this spring 55 to raise the bearing block so as to move the impression cylinder or D-roll out of the operative relation to the plate cylinder. One of these cams is actuated by a gear 58 carrying a stem 59.

Mounted in a screw threaded extension is a 60 micrometer screw 60 co-operating with interior screw threads in said extension and acting upon the bearing block through the stem 59. Said screw is provided with a head 61 having suitable openings therein for a wrench to be used in the 65 manual actuation of the screw.

Carried by the screw adjacent said head 61 is 70 a worm wheel 62, one face of which bears upon a bearing bracket 63 for a worm shaft 64 carrying two worms 65 and 66 co-operating respectively with the worm wheels at opposite ends of the impression cylinder or D-roll.

Carried by the micrometer screw below the bearing bracket 63 is a graduated collar 67 co-operating with which is a gauge finger 68.

75 Bearing upon the top frame of the machine

is a lock nut 69 mounted upon the micrometer screw, this lock nut having an operating handle 70. Between the lock nut and the portion of the screw adjacent the graduated collar is what is known as a safety collar 71 slidably mounted 5 upon the screw threads of the micrometer screw 60.

The shaft 64 has, in the length thereof, two universal joints 72 and 73 to permit the end portions of the worm shaft 64a and 64b to be 10 upon different vertical planes under conditions where a differential adjustment of opposite ends of the impression cylinder or D-roll is required.

Carried adjacent one end of the shaft 64 is a collar 74 having longitudinal channels extending therethrough, as indicated at 75. This collar 15 co-operates with a pin 76 carried by the shaft. Normally, this collar 74 is so set that the pin 76 will engage the end of the collar and thus prevent the reaction from the worm screws imparting any longitudinal movement to the shaft. If the collar, however, is set so that the projecting 20 ends of the pin 76 are in alignment with the slot 75, then by turning the shaft 64, even though the collar 74 be turned with the shaft, the reaction 25 upon the worms 65 and 66 will cause longitudinal movement of the shaft, which is permitted by the sliding of the ends of the pin 76 along the slots 75 in said collar 74. This construction is for the 30 purpose of permitting the worms 65 and 66 to be disengaged from their respective worm gears 62, so as to permit the turning of the micrometer screw independently of the worm shaft.

It will be noted that when either screw 60 is 35 turned independently of the portion of the worm shaft co-operating with the worm wheel 62 carried thereby, said worm gear will be brought to a different horizontal level from the other worm gear, as will one bearing 63 in relation to the other bearing 63. While this ensures the worm 40 65 or 66 upon the worm shaft being properly positioned in relation to its co-operating worm gear, irrespective of the relative position of said gear and the other worm gear, it is necessary to provide the universal joints 72 and 73 in the 45 length of the shaft 64 to compensate for the different levels of the bearings 63 in relation to each other.

The shaft 64 is provided with a squared end, as 50 shown, to permit the use of a wrench or handle in turning said shaft.

Mounted upon the wiper eccentric shaft 20 and the polisher eccentric shaft 27, adjacent each bar, is a collar 77 having a bearing boss 78 concentric with said shaft. Rotatably mounted upon 55 said bearing boss 78 is a member 79 having an eccentric portion co-operating with the strap 24, 25 or 29, having a head flange 80 provided with openings for a wrench. Secured to the bearing boss 78 by means of suitable screws is a clamp 60 plate 81 bearing upon the flange 80. The screws 82 lock the eccentric member 79 in any position in which it may be adjusted, through the clamping action between the plate 81 and the head flange 80. The plate 81 has a sliding fit with the eccentric shaft and is provided with suitable 65 gauge markings adjacent the periphery thereof so as to permit accuracy in the adjustment of the eccentric.

By means of adjustable eccentrics as to each 70 wiping bar, as well as the polishing bar, the timing in the relative movements of these bars may be adjusted in relation to any plate, so as to secure the most effective action of the wiping and polishing webs in relation to that plate. The 75

reciprocating movement of said bars, of course, is determined by the speed of rotation of the shafts 20 and 21, and the adjustment of the eccentric for imparting movement to the wiping or the polishing bars is merely for the purpose of securing a desired movement of each bar in relation to the others in order to determine the proper crossing point of the lines of wipe as to each in relation to the other. This is illustrated in Figs. 3 and 4 of the drawings and will be explained when describing the operation of the machine in its entirety.

The operation of the herein described rotary printing machine is substantially as follows:—

The use of light weight wiper and polisher bars, of counterweighted shafts for reciprocating same, and of the various adjustment and actuating mechanisms described, avoids the development of vibrations in and about the wiping and polishing bars to an extent to permit an effective wiping and polishing of a plate with a speed of rotation of the members of the printing couple greatly in excess of that which was possible in machines of the type to which the invention relates prior to my invention.

Equalization of the pressure between the entire contacting area of the makeready of the impression cylinder or D-roll and the plate, and between the wiper and polisher platens and the plate, not only contributes toward the reduction of vibrations resulting in improper wiping and polishing of the plate, but toward the making of perfect impressions from the plate.

A proper timing of the direct and return reciprocations of the wiper and polisher bars in relation to the travel of the plate, and to each other, permits a more effective wiping and polishing of the plate, and a variation in the wiping and polishing action with plates bearing different designs.

The effect secured by the use of wiper and polisher bars of a metal, such as an aluminum alloy, having low specific gravity as compared with steel and greater rigidity as compared with other light weight materials, and the avoidance of "chattering" of such bars by the use of counterweighted eccentric shafts, has been fully described heretofore.

The use of the various adjustment mechanisms will now be described.

During the makeready of the machine, it is necessary, after a plate has been mounted upon the plate cylinder, to adjust the wiper and polisher bar platens to secure the proper development of the pressure between said platens and the plate; to adjust the several eccentrics to secure a proper timing of the reciprocations of said bars, and to adjust the impression cylinder or D-roll in relation to the plate on the plate cylinder.

The speed of movement of the wiper and polisher bars is fixed by that of the driving shafts 19 and 30 and the gearing 21 and 31 connecting said driving shafts with the wiper and polisher shafts 20 and 21. As heretofore stated, the polisher shaft has greater speed of rotation than the wiper shaft, but the speed reduction between the shafts 19 and 30, effected by the gearing 21, is less than that effected by the gearing 31 between the shafts 20 and 30.

During the makeready of the press, a steel plate 11 is mounted upon the plate cylinder in a position to have the forward edge of the plate engage the nose 33 of the impression cylinder or D-roll when making each impression. The back-
ing sheets 34 and the blanket 35 of the D-roll are

then mounted upon the impression cylinder or D-roll 12. Either the makeready of the impression cylinder or D-roll or the plate may vary in thickness in different portions thereof, although this variation will never be great.

The amount of ink required by the depth and width of the depressed lines upon the plate will also vary in different plates, and in different portions as to each. These conditions sometimes require a different adjustment at opposite ends of the impression cylinder or D-roll in order to establish the proper pressure relation between same and the plate to ensure the proper withdrawal of the ink from the lines of the plate when making an impression.

During the makeready, the shaft 64 is actuated to bring both gauge rings 57, at each end of the impression cylinder or D-roll, to the zero position, thus bringing the arbors of said cylinder or D-roll into proper horizontal alignment. The micrometer screw 43 of each wiper and polisher bar is then actuated to set the gauge sleeve 48 at the zero position, said bars being lowered by the throwoff mechanism including the rack 45, during this adjustment. No adjustment of the eccentrics is required at this stage of the makeready.

Power is then applied to the machine for a trial run.

According to the condition of the impressions made, the following adjustments will then be made:—

The shaft 64 is first actuated to impart vertical adjustment to the bearing blocks 55 by means of the worms 65 and 66 upon the worm shaft 64 and the worm gears 62 carried by the micrometer screws 60 at opposite ends of the impression cylinder or D-roll. If it is found that a perfect impression is secured by this adjustment, no further adjustment of the impression cylinder or D-roll is required. If it is found, however, that the pressure developed toward one end of the cylinder is not sufficiently great, the collar 74 is brought to the position shown in Fig. 5 of the drawings, with the slot therein aligned with the pin 75, so that with subsequent turning of the shaft 64, the worms 65 and 66 will impart no movement to the worm gears 62, but will merely ride out of engagement with said worm gears, thus permitting either screw 60 to be actuated independently of the other until a proper pressure relation between the impression cylinder or D-roll and different portions of the plate is established.

The ends 64a and 64b of the shaft will be brought to parallel horizontal planes with movement of the bearing bracket 63 adjacent the micrometer screw 60 which has been thus independently actuated, this being permitted by the universal joints 72 and 73 in the length of said shaft 64 between said ends 64a and 64b.

By a reverse longitudinal movement of the shaft 64, accompanied by a turning movement of said shaft, said worms 65 and 66 may be re-engaged with both worm gears 62, so that if a subsequent variation of pressure between the impression cylinder or D-roll and the plate is required, the screws 60 operative at each end of said impression cylinder or D-roll may be simultaneously actuated by the turning of the shaft 64, either to increase or relieve the pressure.

When adjusting the impression cylinder or D-roll 12, it should be disengaged from the plate 11, so that this adjustment is merely against the tension of the spring 56 acting upon each

- bearing frame 55. The development of pressure results from the power applied to the impression cylinder or D-roll, following the engagement of the plate with the impression cylinder or D-roll.
- 5 Such adjustments may be required during the run of the machine, due to changing conditions in the makeready of the impression cylinder or D-roll.

Accuracy in the pressure conditions between 10 the impression cylinder or D-roll and the plate avoids any such minor distortion of the plate cylinder, or parts appurtenant thereto, which might interfere with the proper wiping and polishing of the plate, or the setting up of rhythmic vibrations in said plate cylinder.

15 It will be noted that while the impression cylinder or D-roll is adjusted against spring tension, the bearing frames 55 are held against upward movement as a result of the pressures developed 20 by reason of the construction of the adjusting mechanism shown.

During the trial run of the machine, the inking mechanism, not shown in the drawings, is adjusted so as to apply ink to the entire surface 25 of the plate in the quantity required by the design upon the plate.

The various wiper and polisher bars are then moved away from the plate cylinder by the throw-off mechanism operative thereon, and the various 30 screws 43 actuated to bring the gauge sleeve 48 into zero position in relation to the gauge finger 47. While said bars are moved away from the plate cylinder, the wiping and polishing webs, one of which is indicated at A in Fig. 7, are 35 threaded through the machine in the usual manner, one web passing about the heads of the wiping bars 14a and 14b, and a second web passing about the head of the polisher bar 14c. The throwoff mechanism is then actuated to move 40 said bars toward the plate cylinder, and the micrometer screws 43 of each bar may thereafter be actuated to establish the proper pressure relation between the wiper bars and the plate upon the plate cylinder, as determined by the results 45 secured during the trial run of the machine.

The adjustment of the various wiper or polisher bars may be made while they are either in or out of the engaging relation with the plate cylinder. The screws 43 operative upon the opposite ends of 50 each bar may be differentially adjusted according to the conditions developed during the trial run of the machine.

The upper and lower bearings 38 and 39 for the ends of the bars are always in engagement with 55 the bars, and by reason of the use of the posts 37, move with the bars toward or from the plate cylinder. It will be noted that these bearings are so supported by the adjusting screw 43 that a bar can have no movement toward or from the plate cylinder after it is brought into the desired adjusted position, any yielding of the bar in relation to a plate resulting solely from flexibility in the pad 18.

As stated, the spring 52 acting upon the top bearing 38, has no function beyond the holding of the bearing frame in engagement with the head 41 of the adjusting screw, a condition, however, which will result from the action of gravity without the assistance of this spring.

70 The sleeve 48 with its graduations, permits a determination of the amount of adjustment at either end of a bar in relation to the other. These graduation marks represent .001 of an inch, and the spring lock member 51 is operative at intervals of .001 of an inch. Variation in adjustments

of less than this amount is of no moment in securing the desired operation of the wiping and polishing mechanism.

While ordinarily, adjustment of the bearings at opposite ends of the bar will be the same, it is possible to vary the adjustment at one end to a smaller extent in relation to the other end, for the same reasons as adjustment of opposite ends of the impression cylinder or D-roll is sometimes necessary.

10 During the wiping and polishing of the plate, the plate has angular movement and the wiper and polisher bars have movement axially or longitudinally of the plate cylinder. These two combined actions result in a wipe or polish, the action 15 of which is from side to side of a plate with a component of action from end to end of the plate determined by the speed of the wiper or polisher bar and the speed of the press.

This condition is represented in Figs. 3 and 4 20 of the drawings. In Fig. 3, the curve of the wiping action of one wiping bar, as 14a, is shown in full lines at a; the curve of action of the other wiping bar, 14b, is shown in dotted lines at b, and the curve of action of the polisher bar is 25 shown in dot and dash lines at c. The arrow d indicates the direction of movement of the plate, and the arrow e indicates the directions of movement of the various bars. In this figure, the curve is that developed in a rotary printing machine 30 having eight revolutions per minute.

In Fig. 4, I have shown a similar diagram illustrating the wiping and polishing conditions in the machine of the present application, which has a speed of approximately thirty revolutions per 35 minute.

The speeds above referred to are the revolutions of the plate cylinder.

The diagrams are shown in connection with a plate twenty-two and one-half inches in length 40 in each instance, although the diagram would be the same irrespective of the length of the plate, since the curve represents the wiping and polishing operating conditions for each revolution of the plate cylinder.

45 In Fig. 4, the action of the wiping and polishing bars is indicated by the same reference characters as in Fig. 3, as are the arrows indicating the two directions of movement of parts resulting in the curves shown.

50 Two pronounced differences are disclosed in these two diagrams. One of these is in the crossing point of the lines of wipe and polish, and the other is in the number of strokes per revolution of the wiping and polishing bars. It will be borne 55 in mind that these differences do not result merely in the change of the number of revolutions of the plate cylinder per minute, since in each machine represented by these diagrams, the curves would be the same irrespective of the number 60 of revolutions of the plate cylinder because the wiper bar speeds of reciprocation increase proportionately to an increased speed of the plate cylinder. The wiper and polisher bars have a movement from side to side of the plate of approximately one inch, which is the component of movement represented by the arrows e.

65 In the form of the invention shown, the plate has an angular movement of about five and one-half inches during each direct and return reciprocal movement of the wiper or polisher bars, which is a right line movement. Under the conditions shown in Fig. 3, the plate has a movement of only four and one-half inches during one complete reciprocation of the said bars.

It has been found, in actual practice, that the condition shown in Fig. 3 does not admit of a satisfactory wiping and polishing of the plates when the plate cylinder has thirty or more revolutions per minute.

It will be noted that each of the curves in Fig. 4 seems to be flatter than the curves shown in Fig. 3, because of the greater component of movement due to circumferential travel of the plate or the angular movement of the plate cylinder. This condition secures both a more effective wiping and a more effective polishing of the plate at higher speeds of the machine.

To secure this condition, it was found necessary to reduce the number of reciprocations of both the wiper and polisher bars per revolution of the plate cylinder by the speed reducing gearing 14 and 31 connecting the driving shafts 19 and 30 with the wiper eccentric shaft 23 and the polisher eccentric shaft 27 respectively, and to impart a differential speed to the driving shafts 19 and 30, as heretofore described, so as to vary the number of reciprocations of the wiper bars per revolution of the plate cylinder, as compared with the number of reciprocations of the polisher bar, the polisher bar having the greater number of reciprocations.

The angular movement of the plate in relation to the wiping bars, is effective in securing a proper filling and packing of the lines, and notwithstanding the increased number of revolutions per minute of the plate cylinder, with the conditions shown in Fig. 4, as effective filling and packing of the lines of the plate is secured, notwithstanding the higher speed of the press, as under the conditions shown in Fig. 3.

The two wiper bars 14a and 14b and the polisher bar 14c are spaced from each other in the direction of movement of the plate during wiping and polishing, and in order to secure a proper crossing of the lines of wipe, as indicated in Fig. 4, a differential setting of the eccentrics acting upon the respective bars is necessary.

In Fig. 3, a condition is shown which indicates a hit and miss adjustment of said eccentrics, which was found not to be effective when operating the machine at high speeds, for machines of this type.

To permit a control of the lines of crossing of the wipe, I have provided the eccentric adjusting mechanism, shown in Fig. 8, by which the timing of each bar may be accurately set and altered to adapt these mechanisms to any particular plate. By loosening the cap screws 32, the eccentric 78 may be turned upon the bearing boss 79, so as to change the timing of the initiation of each reciprocatory movement of any bar in relation to the other bars.

The collar 77 is secured to the shaft 20 or the shaft 21 so as to be revoluble therewith, and the eccentric 78 may be turned about the axis of said shaft 20 and locked in any adjusted position by means of the clamp plate 81 and the lock screws 82. The gauge markings about the clamp plate 65 facilitate nicely in the adjustment of the clamp plate.

In a machine embodying the invention, the positive support of the bearings for the opposite ends of each wiper or polisher bar prevents the development of rhythmic vibrations in said bars which will interfere with uniformity in the wiping and polishing conditions at all times while the plate is in the operative relation to said bars.

The use of bars of material having low specific gravity, as compared with steel or other metals

commonly used, and possessing a rigidity precluding flexure of the bars either from the initial contact of the edge of the plate with the bar or from the pressures developed by the engagement of the plates with the covering 18 for the head 14 of the bars, reduces the moving inertia of these bars to an extent to permit a smooth reversal of their reciprocatory movements without the development of vibrations or chatter which would interfere with the wiping and polishing action upon the plate.

The use of the counterweights 28 upon the shafts 29 and 27 contributes toward this same end.

By forming the nose 33 of the impression cylinder or D-roll in a curve of long radius, the jars of impact between the forward edge of the plate and the impression cylinder or D-roll are reduced to a minimum, if not entirely eliminated, thus avoiding the development of vibrations in the members of the printing couple which would tend to interfere with a proper action of the wiping and polishing webs. This has been found to be a contributing factor in permitting the stepping up of the speed of the machine in the manner herein described.

The two factors which have been found to contribute most toward the operation of the machine at high speeds are, the elimination of "chatter" during each change in the direction of reciprocation of the wiper and polisher bars, by the use of a bar formed of an aluminum alloy or other metal having a low specific gravity as compared with steel, alone or coupled with the use of counterweights upon the wiper and polisher eccentric shafts, and the control of the number of reciprocations of the wiper and polisher bars with each revolution of the plate cylinder and the timing of the movement of each of these bars in relation to the others, to secure a desired crossing of the lines of wiping action in the manner described. The positive support of the bearings for the various wiper and polisher bars by the adjustment mechanism shown, by which a rhythmic vibration of said bars is prevented as a result of the operation of the machine at high speeds, is also an important factor.

With the operation at high speed of a machine in which heavy pressures are required, as in machines of the type herein described, and in which the plate is intermittently engaged with, and disengaged from, the impression cylinder or D-roll and the wiping and polishing bars, the tendency toward the setting up of vibrations is greater than with the operation of the machine at lower speeds, and the various mechanisms herein described have been found to operate successfully in reducing the amount of such vibration to a point where a very high speed of the machine may be attained, although if a speed in excess of between thirty and forty revolutions per minute is attained, vibrations interfering with a proper wiping and polishing of the plate may develop.

The machine herein described is particularly adapted for use with one plate upon the plate cylinder, and if two plates are used, a slowing down of the machine becomes necessary to avoid the effects of vibration occurring during the making of an impression from one plate, while the wiping and polishing mechanism is operative upon the other plate.

While the use of light weight wiper and polisher bars, and the provision of adjustment means for the timing of the reciprocation of said bars in

relation to each other will permit an increase in the speed of operation of a machine of the type herein described, the construction of the bearings for the ends of the various bars, the accurate adjustment of the impression cylinder or D-roll, and the form of the nose of the impression cylinder or D-roll each are contributing factors in securing the maximum speed of operation of the machine with a minimum of imperfect 10 pressions.

It is not my intention to limit the invention to the precise details of construction shown in the accompanying drawings, nor to the use of all of the contributing features, it being obvious that such details of construction may be varied without departing from the spirit and scope of the invention, and some of the advantageous characteristics may be omitted and yet permit the operation of the machine at a higher speed than that heretofore attained by machines of this type.

Having described the invention, what I claim as new and desire to have protected by Letters Patent, is:

1. A rotary printing machine embodying therein a plate cylinder having a peripheral speed in excess of 175 feet per minute, an impression cylinder or D-roll, a wiping mechanism including therein a wiper bar, a wiper shaft, and means whereby said bar is reciprocated from said shaft, a polishing mechanism including therein a polisher bar, a polisher shaft, and means whereby said bar is reciprocated from said shaft, and means minimizing vibration of said bars from moving inertia upon reversal of the movements of said bars, including therein speed reducing gearing operative upon said shafts respectively, whereby with high angular speed of said plate cylinder, said bars will have a plurality of slow reciprocatory movements with each revolution of said plate cylinder, the wiper bar having one full reciprocation with substantially five inches of travel of the plate cylinder.

2. A rotary printing machine embodying therein a plate cylinder having a peripheral speed in excess of 175 feet per minute, an impression cylinder or D-roll, a wiping mechanism including therein a wiper bar, a wiper shaft, and means whereby said bar is reciprocated from said shaft, a polishing mechanism including therein a polisher bar, a polisher shaft, and means whereby said bar is reciprocated from said shaft, and means minimizing vibration of said bars from moving inertia upon reversal of the movements of said bars, including therein speed reducing gearing operative upon said wiper shaft and speed reducing gearing operative upon said polisher shaft, whereby with high angular speed of said plate cylinder, said bars will have a plurality of slow reciprocatory movements with each revolution of said plate cylinder, the polisher bar having one full reciprocation with substantially four inches of travel of the plate cylinder, the gearing operative upon said wiper shaft, and the gearing operative upon said polisher shaft, being relatively so proportioned as to impart a greater reciprocatory speed to said polisher bar than to said wiper bar.

3. A rotary printing machine embodying therein a plate cylinder having a peripheral speed in excess of 175 feet per minute, an impression cylinder or D-roll, a wiping mechanism including therein a plurality of wiper bars, a wiper shaft, and a plurality of means upon said shaft and operative upon said bars respectively, whereby said bars are reciprocated, a polishing

mechanism including therein a polisher bar, a polisher shaft, and means whereby said bar is reciprocated from said shaft, and means minimizing vibrations of said bars from moving inertia upon reversal of the movements of said bars, including therein speed reducing gearing operative upon said shafts respectively, whereby with high angular speed of said plate cylinder, said bars will have a plurality of slow reciprocatory movements with each revolution of said plate cylinder, the wiper bar having one full reciprocation with substantially five inches of travel of the plate cylinder, and the polisher bar having one full reciprocation with substantially four inches of travel of the plate cylinder.

4. A rotary printing machine embodying therein a plate cylinder, an impression cylinder or D-roll, a wiping mechanism including therein a wiper bar, a wiper shaft, an eccentric upon said wiper shaft, a strap co-operating with said eccentric and with said wiper bar, and means whereby said eccentric may be adjusted about its shaft, a polishing mechanism including therein a polisher bar, a polisher shaft, an eccentric upon said polisher shaft, a strap co-operating with said eccentric and with said polisher bar, and means whereby said eccentric may be adjusted about its shaft, and means minimizing vibration of said bars from moving inertia upon reversal of the movements of said bars, including therein speed reducing gearing operative upon said shafts respectively, whereby with high angular speed of said plate cylinder, said bars will have a plurality of slow reciprocatory movements with each revolution of said plate cylinder.

5. A rotary printing machine embodying therein a plate cylinder, an impression cylinder or D-roll, a wiping mechanism including therein a plurality of wiper bars, a wiper shaft, a plurality of eccentrics upon said shaft, a strap co-operating with each eccentric and with a wiper bar, and means whereby each eccentric may be adjusted about its shaft to regulate the timing of the crossing of the lines of wipe, a polishing mechanism including therein a polisher bar, a polisher shaft, and means whereby said bar is reciprocated from said shaft, and means minimizing vibration of said bars from moving inertia upon reversal of the movements of said bars, including therein speed reducing gearing operative upon said shafts respectively, whereby with high angular speed of said plate cylinder, said bars will have a plurality of slow reciprocatory movements with each revolution of said plate cylinder.

6. A rotary printing machine embodying therein a plate cylinder, an impression cylinder or D-roll, a wiping mechanism including therein a plurality of wiper bars, a wiper shaft, a plurality of eccentrics upon said shaft, a strap co-operating with each eccentric and with a wiper bar, and means whereby each eccentric may be adjusted about its shaft to regulate the timing of the crossing of the lines of wipe, a polishing mechanism including therein a polisher bar, a polisher shaft, an eccentric carried by said polisher shaft, a strap co-operating therewith and with said polisher bar, and means for adjusting said polisher bar eccentric about its shaft to regulate the polishing action of said polisher bar with relation to the wiping action of said wiper bars, and means minimizing vibration of said bars from moving inertia upon reversal of the movements of said bars, including therein speed reducing gearing operative upon said shafts respectively,

whereby with high angular speed of said plate cylinder, said bars will have a plurality of slow reciprocatory movements with each revolution of said plate cylinder.

7. A rotary printing machine embodying therein a plate cylinder, an impression cylinder or D-roll, a wiping mechanism including therein a wiper bar, a wiper shaft, an eccentric upon said wiper shaft, a strap co-operating with said eccentric and with said wiper bar, and means whereby said eccentric may be adjusted about its shaft, a polishing mechanism including therein a polisher bar, a polisher shaft, an eccentric upon said polisher shaft, a strap co-operating with said eccentric and with said polisher bar, and means whereby said eccentric may be adjusted about its shaft, the adjusting means for each said eccentric comprising a collar having a bearing boss secured to the shaft upon which the eccentric is revolvably mounted, means carried by the eccentric whereby it may be turned upon said boss, a clamp plate mounted upon said shaft, and means acting upon said clamp plate and upon said bearing boss whereby the eccentric may be locked in any adjusted position, and means minimizing vibration of said bars from moving inertia upon reversal of the movements of said bars, including therein speed reducing gearing operative upon said shafts respectively, whereby with high angular speed of said plate cylinder, said bars will have a plurality of slow reciprocatory movements with each revolution of said plate cylinder.

8. A rotary printing machine embodying therein a plate cylinder, an impression cylinder or D-roll, a wiping mechanism including therein a plurality of wiper bars, a wiper shaft, a plurality of eccentrics upon said shaft, a strap co-operating with each eccentric and with a wiper bar, and means whereby each eccentric may be adjusted about its shaft to regulate the timing of the crossing of the lines of wipe, a polishing mechanism including therein a polisher bar, a polisher shaft, an eccentric carried by said polisher shaft, a strap co-operating therewith and with said polisher bar, and means for adjusting said polisher bar eccentric about its shaft to regulate the polishing action of said polisher bar with relation to the wiping action of said wiper bars, the adjusting means for each said eccentric comprising a collar having a bearing boss secured to the shaft upon which the eccentric is revolvably mounted, means carried by the eccentric whereby it may be turned upon said boss, a clamp plate mounted upon said shaft, and means acting upon said clamp plate and upon said bearing boss whereby the eccentric may be locked in any adjusted position, and means minimizing vibration of said bars from moving inertia upon reversal of the movements of said bars, including therein speed reducing gearing operative upon said shafts respectively, whereby with high angular speed of said plate cylinder, said bars will have a plurality of slow reciprocatory movements with each revolution of said plate cylinder.

9. A rotary printing machine embodying therein a plate cylinder, an impression cylinder or D-roll, a wiping mechanism including therein a wiper bar, means for imparting reciprocatory movement to said bar, bearings for the opposite ends of said bar each including an upper bearing plate and a lower bearing plate, said plates being movable toward and from said plate cylinder, and means connecting said plates, said bar having polygonal ends having a free sliding fit be-

tween said bearing plates, and means including an adjustment screw operative upon said lower bearing plate to impart positive movement of said bearing plates and the bar mounted therein, toward or from the plate cylinder, whereby the ends of the bar are positively and non-yieldingly supported in relation to said plate cylinder.

10. A rotary printing machine embodying therein a plate cylinder, an impression cylinder or D-roll, a wiping mechanism including therein a wiper bar, means for imparting reciprocatory movement to said bar, bearings for the opposite ends of said bar each including an upper bearing plate and a lower bearing plate, said plates being movable toward and from said plate cylinder, and means connecting said plates, said bar having polygonal ends having a free sliding fit between said bearing plates, and means including an extension upon said lower bearing plate having a T-slot therein, an interiorly screw threaded member below the bearing plates, a micrometer screw having an enlarged head mounted in said T-slot and co-operating with the screw threads of said screw threaded member, a graduated collar carried by said micrometer screw, and an index finger adjacent said collar, whereby positive movement may be imparted to said bearing plates and the bar mounted therein, toward or from the plate cylinder, and the ends of the bar will be positively and non-yieldingly supported in relation to said plate cylinder.

11. A rotary printing machine embodying therein a plate cylinder, an impression cylinder or D-roll, a wiping mechanism including therein a wiper bar, means for imparting reciprocatory movement to said bar, bearings for the opposite ends of said bar each including an upper bearing plate and a lower bearing plate, said plates being movable toward and from said plate cylinder, and means connecting said plates, said bar having polygonal ends having a free sliding fit between said bearing plates, and means including an extension upon said lower bearing plate having a T-slot therein, a rack having screw threads therein forming a part of a throwoff mechanism for said bar below the bearing plates, a micrometer screw having an enlarged head mounted in said T-slot and co-operating with the screw threads of said rack, a graduated collar carried by said micrometer screw, and an index finger adjacent said collar, whereby positive movement may be imparted to said bearing plates and the bar mounted therein, toward or from the plate cylinder, and the ends of the bar will be positively and non-yieldingly supported in relation to said plate cylinder.

12. A rotary printing machine embodying therein a plate cylinder, an impression cylinder or D-roll, a wiping mechanism including therein a plurality of wiper bars, a polishing mechanism including therein a polisher bar, means for imparting reciprocatory movement to said wiper and polisher bars respectively, bearings for the opposite ends of each of said bars, each said bearing including an upper bearing plate and a lower bearing plate, said plates being movable toward and from said plate cylinder, and means connecting said plates, said bar having polygonal ends having a free sliding fit between said bearing plates, and means including an adjustment screw operative upon said lower bearing plate to impart positive movement of said bearing plates and the bar mounted therein, toward or from the plate cylinder, whereby the ends of the bar are positively supported in relation to said plate cylinder.

and non-yieldingly supported in relation to said plate cylinder.

13. A rotary printing machine embodying therein a plate cylinder, an impression cylinder or D-roll, a wiping mechanism including therein a wiper bar, a polishing mechanism including therein a polisher bar, and means for imparting reciprocatory movement to said bars respectively, said wiper bar being formed of a metal having low specific gravity as compared with steel and high compressive strength, whereby with high angular speed of said plate cylinder, said bars will have a plurality of slow reciprocatory movements with each revolution of said plate cylinder, and excessive moving inertia in said wiper bar will be avoided.

14. A rotary printing machine embodying therein a plate cylinder, an impression cylinder or D-roll, a wiping mechanism including therein a wiper bar, a polishing mechanism including therein a polisher bar, and means for imparting reciprocatory movement to said bars respectively, said polisher bar being formed of a metal having low specific gravity as compared with steel and high compressive strength, whereby with high angular speed of said plate cylinder, said polisher bar will have a plurality of slow reciprocatory movements with each revolution of said plate cylinder, and excessive moving inertia in said polisher bar will be avoided.

15. A rotary printing machine embodying therein a plate cylinder, an impression cylinder or D-roll, a wiping mechanism including therein a wiper bar, a polishing mechanism including therein a polisher bar, and means for imparting reciprocatory movement to said bars respectively, said wiper and said polisher bars each being formed of a metal having low specific gravity as compared with steel and high compressive strength, whereby with high angular speed of said plate cylinder, said bars will have a plurality of slow reciprocatory movements with each revolution of said plate cylinder, and excessive moving inertia in said wiper and polisher bars will be avoided.

16. A rotary printing machine embodying therein a plate cylinder, an impression cylinder or D-roll, a wiping mechanism including therein a wiper bar, a wiper shaft, a counter-weight upon said shaft, and means whereby said bar is reciprocated from said shaft, a polishing mechanism including therein a polisher bar, a polisher shaft, and means whereby said bar is reciprocated from said shaft, and means minimizing vibration of said bars from moving inertia upon reversal of the movements of said bars, including therein speed reducing gearing operative upon said shafts respectively, whereby with high angular speed of said plate cylinder, said bars will have a plurality of slow reciprocatory movements with each revolution of said plate cylinder.

17. A rotary printing machine embodying therein a plate cylinder, an impression cylinder or D-roll, a wiping mechanism including therein a wiper bar, a wiper shaft, and means whereby said bar is reciprocated from said shaft, a polishing mechanism including therein a polisher bar, a polisher shaft, a counterweight upon said shaft, and means whereby said bar is reciprocated from said shaft, and means minimizing vibration of said bars from moving inertia upon reversal of the movements of said bars, including therein speed reducing gearing operative upon said shafts respectively, whereby with high angular speed of said plate cylinder, said bars will have a plurality

of slow reciprocatory movements with each revolution of said plate cylinder.

18. A rotary printing machine embodying therein a plate cylinder, an impression cylinder or D-roll, a wiping mechanism including therein a wiper bar, a wiper shaft, a counterweight upon said shaft, and means whereby said bar is reciprocated from said shaft, a polishing mechanism including therein a polisher bar, a polisher shaft, a counterweight upon said shaft, and means whereby said bar is reciprocated from said shaft, and means minimizing vibration of said bars from moving inertia upon reversal of the movements of said bars, including therein speed reducing gearing operative upon said shafts respectively, whereby with high angular speed of said plate cylinder, said bars will have a plurality of slow reciprocatory movements with each revolution of said plate cylinder.

19. A rotary printing machine embodying therein a plate cylinder, an impression cylinder or D-roll, a wiping mechanism including therein a wiper bar, a wiper shaft, a counterweight upon said shaft, and means whereby said bar is reciprocated from said shaft, a polishing mechanism including therein a polisher bar, a polisher shaft, and means whereby said bar is reciprocated from said shaft, and means minimizing vibration of said bars from moving inertia upon reversal of the movements of said bars, including therein speed reducing gearing operative upon said shafts respectively, said wiper bar being formed of a metal having low specific gravity as compared with steel and high compressive strength, whereby with high angular speed of said plate cylinder, said bars will have a plurality of slow reciprocatory movements with each revolution of said plate cylinder, and said counterweight will be made more effective in avoiding excessive moving inertia in said wiper bar.

20. A rotary printing machine embodying therein a plate cylinder, an impression cylinder or D-roll, a wiping mechanism including therein a wiper bar, a wiper shaft, and means whereby said bar is reciprocated from said shaft, a polishing mechanism including therein a polisher bar, a polisher shaft, a counterweight upon said shaft, and means whereby said bar is reciprocated from said shaft, and means minimizing vibration of said bars from moving inertia upon reversal of the movements of said bars, including therein speed reducing gearing operative upon said shafts respectively, said polisher bar being formed of a metal having low specific gravity as compared with steel and high compressive strength, whereby with high angular speed of said plate cylinder, said bars will have a plurality of slow reciprocatory movements with each revolution of said plate cylinder, and said counterweight will be made more effective in avoiding excessive moving inertia in said polisher bar.

21. A rotary printing machine embodying therein a plate cylinder, an impression cylinder or D-roll, a wiping mechanism including therein a wiper bar, a wiper shaft, a counter-weight upon said shaft, and means whereby said bar is reciprocated from said shaft, a polishing mechanism including therein a polisher bar, a polisher shaft, a counterweight upon said shaft, and means whereby said bar is reciprocated from said shaft, and means minimizing vibration of said bars from moving inertia upon reversal of the movements of said bars, including therein speed reducing gearing operative upon said shafts respectively, said wiper and said polisher bars each

- being formed of a metal having low specific gravity as compared with steel and high compressive strength, whereby with high angular speed of said plate cylinder, said bars will have a plurality of slow reciprocatory movements with each revolution of said plate cylinder, and said counterweights will be made more effective in avoiding excessive moving inertia in said wiper and polisher bars.
22. A rotary printing machine embodying therein a plate cylinder, an impression cylinder or D-roll, a wiping mechanism including therein a wiper bar, a wiper shaft, a counterweight upon said shaft, an eccentric upon said wiper shaft, and a strap co-operating with said eccentric and with said wiper bar, a polishing mechanism including therein a polisher bar, a polisher shaft, a counterweight upon said shaft, an eccentric upon said polisher shaft, and a strap co-operating with said eccentric and with said polisher bar, and means minimizing vibration of said bars from moving inertia upon reversal of the movements of said bars, including therein speed reducing gearing operative upon said shafts respectively, said wiper and polisher bars each being formed of a metal having low specific gravity as compared with steel and high compressive strength, whereby with high angular speed of said plate cylinder, said bars will have a plurality of slow reciprocatory movements with each revolution of said plate cylinder, and said counterweights will be made more effective in avoiding excessive moving inertia in said wiper and polisher bars.
23. A rotary printing machine embodying therein a plate cylinder, an impression cylinder or D-roll, the portion of said impression cylinder or D-roll which initially engages a plate upon said plate cylinder being formed in an arc of long radius, whereby vibration resulting from the jar of contact of said impression cylinder or D-roll with the forward edge of a plate is minimized, a wiping mechanism including therein a wiper bar, a wiper shaft, and means whereby said bar is reciprocated from said shaft, a polishing mechanism including therein a polisher bar, a polisher shaft, and means whereby said bar is reciprocated from said shaft, and means minimizing vibration of said bars from moving inertia upon reversal of the movements of said bars, including therein speed reducing gearing operative upon said shafts respectively, whereby with high angular speed of said plate cylinder, said bars will have a plurality of slow reciprocatory movements with each revolution of said plate cylinder.
24. A rotary printing machine embodying therein a plate cylinder, an impression cylinder or D-roll, vertically movable bearings for the opposite ends of said impression cylinder or D-roll, adjusting means operative upon said bearings respectively, an actuating mechanism simultaneously operative upon both of said adjusting means including therein means whereby the portion of said actuating mechanism engageable with said adjusting means respectively may move vertically with the adjusting means into different horizontal planes, a wiping mechanism including therein a wiper bar, a wiper shaft, and means whereby said bar is reciprocated from said shaft, a polishing mechanism including therein a polisher bar, a polisher shaft, and means whereby said bar is reciprocated from said shaft, and means minimizing vibration of said bars from moving inertia upon reversal of the movements of said bars, including therein speed reducing gearing operative upon said shafts respectively, whereby with high angular speed of said plate cylinder, said bars will have a plurality of slow reciprocatory movements with each revolution of said plate cylinder.
25. A rotary printing machine embodying therein a plate cylinder, an impression cylinder or D-roll, vertically movable bearings for the opposite ends of said impression cylinder or D-roll, adjusting means operative upon said bearings respectively, an actuating mechanism simultaneously operative upon both of said adjusting means, means whereby said actuating mechanism may be selectively engaged with, or disengaged from, said adjusting means respectively, means included in said actuating mechanism whereby the portion of said actuating mechanism engageable with said adjusting means respectively may move vertically with the adjusting means into different horizontal planes, a wiping mechanism including therein a wiper bar, a wiper shaft, and means whereby said bar is reciprocated from said shaft, a polishing mechanism including therein a polisher bar, a polisher shaft, and means whereby said bar is reciprocated from said shaft, and means minimizing vibration of said bars from moving inertia upon reversal of the movements of said bars, including therein speed reducing gearing operative upon said shafts respectively, whereby with high angular speed of said plate cylinder, said bars will have a plurality of slow reciprocatory movements with each revolution of said plate cylinder.
26. A rotary printing machine embodying therein a plate cylinder, an impression cylinder or D-roll, vertically movable bearings for the opposite ends of said impression cylinder or D-roll, a micrometer screw operative upon each said bearing, a worm wheel carried by each of said screws, a worm shaft co-operating with said worm wheels respectively, a bearing for said worm shaft adjacent to, and movable with, said worm wheels respectively, means whereby said worm shaft may be flexed intermediate said bearings, means permitting disengagement of said worm shaft from, or its engagement with, said worm wheels, whereby said micrometer screws may be independently actuated or simultaneously actuated, irrespective of the vertical position of the worm wheels upon said micrometer screws, to regulate the pressure relation between said impression cylinder or D-roll and a plate upon said plate cylinder, a wiping mechanism including therein a wiper bar, a wiper shaft, and means whereby said bar is reciprocated from said shaft, a polishing mechanism including therein a polisher bar, a polisher shaft, and means whereby said bar is reciprocated from said shaft, and means minimizing vibration of said bars from moving inertia upon reversal of the movements of said bars, including therein speed reducing gearing operative upon said shafts respectively, whereby with high angular speed of said plate cylinder, said bars will have a plurality of slow reciprocatory movements with each revolution of said plate cylinder.
